UNITED STATES PATENT OFFICE.

CHARLES H. NEWMAN, OF BROOKLYN, NEW YORK.

IRONING-BOARD SUPPORT.

1,147,538.

Specification of Letters Patent. Patented July 20, 1915.

Application filed March 3, 1915. Serial No. 11,846.

To all whom it may concern:

Be it known that I, CHARLES H. NEWMAN, a citizen of the United States, residing at Brooklyn, in the county of Kings and State of New York, have invented new and useful Improvements in Ironing-Board Supports, of which the following is a specification.

This invention relates to supports for ironing boards and it consists in the novel 10 features hereinafter described and claimed.

An object of the invention is to provide a support of simple and durable structure and adapted to be mounted upon a fixed object in a manner whereby the board may be 15 easily and quickly detached from the support when desired. The parts of the support are so arranged that when the board is in position thereon it is securely held and the under side of the board is left without 20 obstructions so that the clothes may be readily positioned upon the board for ironing or pressing.

With the above objects in view the support comprises two members preferably formed 25 from cast metal one of the said members being adapted to be mounted upon a fixed object and the other member frictionally engaging the first mentioned member. When the 30 board is applied to the support it is retained in position between the said members.

In the accompanying drawing, Figure 1 is a perspective view of an ironing board applied to the support. Fig. 2 is an edge elevation of an end portion of the same. 35 Fig. 3 is a perspective view of the base member and Fig. 4 is a perspective view of the plate member about to be described.

The support comprises a base member 1 adapted to be secured to a fixed object by 40 means of screws 2 or other suitable securing devices. Lugs 3 are formed upon the upper side of the member 1 in spaced relation and are provided with converging and inclined inner faces 4. The lugs 3 are located at one end of the member 1 and the 45 upper surface of the member 1 at the opposite end is inclined or beveled as at 5. The member 1 is preferably formed from cast metal. Inasmuch as the member 1 is adapted 50 to be secured to a fixed object it will be hereinafter referred to as the base member. The support also includes a plate member 6 having formed integral therewith a wedge shaped post 7 adapted to fit snugly between 55 the faces 4 of the lugs 3 and frictionally engage the same. When the member 6 is

applied to the member 1 the end of the post 7 rest squarely upon the upper surface of the member 1 at the part thereof which is located between the lug 3, as best indicated 60 in Fig. 2 of the drawing. The body portion of the plate member 6 lies above the beveled surface 5 of the member 1 and the member 6 is provided at its under side with a series of transversely disposed ridges and some of 65 the said ridges are disposed at the upper under side of the post 7. The plate member 6 is provided with an opening 9 which reduces the metal of the said member and also the weight thereof, and in view of the 70 fact that the said opening is located in the plate within the portion thereof upon which an iron may rest the said plate is not heated to an excessive degree when a hot iron is placed thereon. The plate member 6 is provided upon its upper side with a series of 75 lugs 10 which serve as guides and stops for directing the iron to a proper position upon the plate when it is placed on the same and also for holding the iron upon position upon 80 the plate. The plate member 6 and its component parts are preferably formed from cast metal.

A board 11 of the usual configuration may be inserted at its ends between the members 85 1 and 6 in a manner best shown in Fig. 2 of the drawing and thus the board is supported with the major portion of its length projecting beyond the object upon which the member 1 is mounted. Consequently the 90 clothes may be easily and quickly applied to the board for ironing or pressing. By reason of the fact that the upper surface of the member 1 is chamfered or beveled as at 95 5 a wedge-shaped recess is provided between the members 1 and 6 for the reception and direction of the end of the board 11 between the said members. When the board 11 is inserted between the members the ridges 8 engage the upper surface of the board (as 100 shown in Fig. 2) and thus the board is securely and efficiently held in place with relation to the support.

Having described the invention what is claimed is:—

1. A board holder comprising a member adapted to be applied to an object, a plate member detachably engageable with the first mentioned member, there being a recess between the said members when connected, 110 said recess adapted to receive the edge portion of a board.

2. A board holder comprising a base member and a plate member adapted to detachably engage the base member, there being a recess between the said members for the reception of the edge portion of the board, one of the members being provided with transversely disposed ribs adapted to engage the board.
3. A board holder comprising a member provided with up-standing spaced lugs, a plate member having a post adapted to fit snugly between the lugs there being a recess between the said members for the reception of the edge portion of a board.
4. A board holder comprising a base member having up-standing lugs provided with inclined and converging inner faces, a plate member having a wedge-shaped post adapted to fit snugly against the faces of the lugs

there being a space between the members 20 for the reception of the edge portion of a board.

5. A board holder comprising a member provided at one end with upstanding lugs spaced from each other and at its other end 25 with a chamfered upper surface, a plate member having a post adapted to fit snugly between the lugs and against the upper surface of the member there being a recess between the said members and above the said 30 chamfered surface of the base member for the reception of the edge portion of a board.

In testimony whereof I affix my signature in presence of two witnesses.

CHARLES H. NEWMAN.
